[57] ABSTRACT

In a fast linear or toroidal zeta pinch device a discharge tube which fits precisely into the primary winding of said device, said tube being a series of anodized aluminum rings stacked upon each other and held together by a nonconducting epoxy layer which is coated with a slightly conducting layer, and then an outer structural layer.

ALL-METAL DISCHARGE TUBE

BACKGROUND OF THE INVENTION

The invention described herein was made in the course of, or under, a contract with the U.S. Atomic Energy Commission.

The present invention relates to a device which can be used as the tube containing the plasma in a zeta pinch device. In the past these discharge tubes were made of ceramic materials such as quartz or alumina. The advantages to be gained using a metal tube over the ceramic are as follows:

1. A metal conductor can absorb high energy pulses on the surface exposed to the plasma without melting due to its higher thermal conductivity.

2. The contamination of the plasma by a wall material released by evaporation and ion bombardment can be made less by a careful choice of the wall material. In particular, losses by bremsstrahlung radiation are approximately Z^2 (Z being the atomic number) and thus using low Z metals the radiation is reduced substantially.

3. Fabrication of a discharge tube which closely fits inside the primary of the zeta pinch device is made easier if machined out of metal. In the past it has been difficult to procure ceramic or quartz tubes which do not add prohibitively to the inductance.

A figure of merit ($Qt^{1/2}$) has been determined for evaluating various materials. It has been calculated that the temperature rise (ΔT) of a surface for a flux Q of energy is given by

$$\Delta T = 2Q(t/\pi Ck\rho)^{1/2}$$

where

t = time,

C = thermal conductivity,

k = thermal capacity and

ρ = specific heat.

With ΔT determined by the melting point it is clear that metals are superior to insulators since metals have a higher thermal conductivity C . However, with metals the question arises how to reconcile the conflict between the high electrical conductivity of the wall and the necessity for the axial electric field in a zeta pinch. For slow linear and toroidal devices such as Zeta and Tokamaks it is practicable to use corrugated thin walls to keep the wall currents to tolerable proportions by resistance. For the fast linear and toroidal zeta pinch devices with high field gradients ($E_z \approx 1$ kilovolt per centimeter), the wall currents would be too large for a practical tube. There are two other ways by which wall currents can be reduced other than high resistance, e.g., (1) by subdivision of the wall, and (2) by high inductance. In the design of the fast linear or toroidal zeta pinch device at least four criteria must be satisfied.

1. The material must have a high melting temperature to absorb energy flux from the plasma without vaporizing the surface. A conductor can absorb higher energy pulses on the surface exposed to the plasma without melting due to its higher thermal conductivity.

2. The design must allow high electric fields, approximately 1 kilovolt per centimeter, to be applied along the tube.

3. Dimensional tolerances are tight.

4. The tube must be able to withstand being pumped down to a low pressure.

SUMMARY OF THE INVENTION

A series of aluminum rings were stacked on top of each other. Aluminum was chosen as the material not because it has the most desirable thermal properties but the surfaces can be anodized and thus prevent arcing between each of the rings. A total of 800 rings formed a discharge tube length of approximately 9 1/2 inches. Tests have shown that 300 volts could be applied between adjacent rings without breakdown. The outer coaxial current return has also introduced a difficulty with this design. The capacity of each ring to ground, although much smaller than the inter-ring capacity, meant that the applied high voltage is not uniformly divided down the ring train. This difficulty can be avoided by grading the volt-

age uniformly down the ring assembly by surrounding the system with a relatively high resistance. In the present device we use a carbon-loaded epoxy having a resistance of about 150 ohms as the slightly conducting layer. The slightly conducting layer is necessary to smooth the voltage gradient down the length of the discharge tube. Without this layer most of the voltage of a short electrical pulse will be applied across only a few of the rings at the high voltage end of the tube. A catastrophic breakdown of the insulation between rings will occur. Meanwhile, the resistivity must be high enough that it does not completely short out the main discharge. An outer layer of fiberglass cloth impregnated with epoxy gives strength to the assembly while the innermost layer is an epoxy which cements the rings together.

The primary object of this invention is to provide a discharge tube useful in containing a hot plasma, said tube being stable in the presence of the hot plasma and also being able to withstand extreme amperage and high voltage generated in a relatively short period in zeta pinch device.

This object and other objects and advantages are set forth hereinafter in the following description of the preferred embodiment and drawings.

BRIEF DESCRIPTION OF THE DRAWINGS

FIG. 1 is a schematic cross-sectional view of a linear discharge tube of this invention along centerline C_L while

FIG. 2 is a schematic view of the problem solved by this invention.

Referring to FIG. 1, there is shown the stacked rings 1 which are anodized on their flat surfaces 5 and are held together by a nonconducting triple layer consisting of an epoxy 3 which cements the rings together and holds the vacuum, a thin metallic but slightly conducting coating 4, and an outer epoxy coating which is impregnated in a fiber glass cloth 2 which wraps the entire discharge tube and gives it structural strength.

DESCRIPTION OF PREFERRED EMBODIMENT

In the preferred embodiment shown in FIG. 1, the aluminum ring 1 is anodized on its flat surfaces 5. The rings are held together by any nonconducting compound such as an epoxy with appropriate hardeners added. The approximate dimensions of the ring are: height 0.010 inch; width, 0.30 inch; epoxy layer 3, 0.010 inch radial thick; slight conducting layer 4, 0.10 inch thick; and fiber glass impregnated with epoxy, about 0.1 inch thick. (FIG. 1 is not to scale.)

Although the inventors have disclosed a triple layer surrounding the exterior of the tube, the said invention is not limited by these restrictions since these layers only perform the function of (a) holding the rings together and vacuum within the tube, (b) a conducting layer that smooths the voltage gradient down the length of the discharge tube, and (c) the fiber glass cloth wrap impregnated with epoxy gives structural strength to the discharge tube.

Referring now to FIG. 2, there is shown the aluminum rings 1 with their anodized surfaces 5 and positioned inside the primary 6 of the zeta pinch device. The capacitance denoted as C_2 is the capacitance of the inner rings generated when high voltage is applied through the primary conductor 6. Capacitance denoted as C_1 is the capacity of each ring to ground and is much smaller in value than the inner ring capacity C_2 .

In the prior art alumina and quartz were used as discharge tubes but the alumina became quite friable after several discharges which caused it to crack or chip off and thus degrade the plasma stream which it surrounds. Quartz tended to vaporize and dilute the plasma. The alumina ring device of the present invention is very stable in a high voltage field and because of its anodized surfaces there is no arcing between the rings and the epoxy wrap has a much lower inductance than either the alumina or quartz.

The tube has been installed in the Columbia experiment and connected to the zeta pinch power supply. Vacuum pressures of $< 5 \times 10^{-6}$ mTorr were reached after 24 hours of pumping. Magnetic probe measurements have shown that a discharge pulls away from the wall with Z-electric fields ≤ 1.3 kilovolt per centimeter before gas breakdown with a peak discharge current of 500 kiloamps. Inspection of the tube after approximately 200 discharges has shown no damage.

What we claim is:

1. In a zeta pinch plasma device, an improved discharge tube which fits precisely into the primary winding of said device, said tube comprising a series of 0.010-inch-thick aluminum rings stacked upon each other and anodized on each flat surface, said rings being held together by an intermediate layer that is slightly conducting and acts as a voltage divider for said rings, and an outer nonconducting structural layer.
2. The tube of claim 1 in which its shape is linear.
3. The tube of claim 1 in which its shape is toroidal.
4. The inner layer of claim 1 comprising an epoxy with appropriate hardeners added.
5. The intermediate layer of about 150 ohms.
6. The outer nonconducting layer of claim 1 comprising a fiber glass cloth impregnated with an epoxy.

* * * * *

The critical criteria for the device of this invention are as follows:

1. The insulation between adjacent layers (the anodized coating with aluminum) must hold off approximately 300 volts.

2. The thickness for each ring must be such that when the applied electric field (approximately 1.0 kilovolts per centimeter) is divided by the number of rings per centimeter the voltage between rings is less than 20-25 volts. If the voltage is greater, a power arc will develop and the discharge tube fails.

The radial width of each ring must be approximately 1 meter thick to absorb the bremsstrahlung radiation from the shots (discharges). The layer immediately outside the tube must be strong enough to pass the voltage divider must be strong enough to pass the voltage down the tube.

The assembly together.
